W. F. STREICH,
DRAWER STABILIZER,
APPLICATION FILED DEC. 26, 1919.

1,352,924.

Patented Sept. 14, 1920.

UNITED STATES PATENT OFFICE.

WILLIAM F. STREICH, OF DETROIT, MICHIGAN

DRAWER-STABILIZER.

1,352,924.

Specification of Letters Patent. Patented Sept. 14, 1920.

Application filed December 26, 1919. Serial No. 347,362.

To all whom it may concern:

Be it known that I, WILLIAM F. STREICH, a citizen of the United States of America, and a resident of Detroit, in the county of 5 Wayne and State of Michigan, have invented a new and useful Improvement in Drawer-Stabilizers, of which the following is a specification.

The object of my invention is a means for 10 guiding a drawer accurately in place, for preventing rattling between the drawer and the sides of the cabinet or casing, and for preventing lateral movement between the drawer and the walls of the casing, after the 15 drawer has been closed.

These and other objects are attained by the means described in the specification and illustrated in the accompanying drawing, in which:—

20 Figure 1, is a perspective view of a drawer stabilizer embodying my invention, the parts being shown in an extended position.

Fig. 2, is a perspective view upon an enlarged scale of my drawer stabilizer, showing the parts in their closed position.

Fig. 3, is a front elevation of a modified form of my drawer stabilizer.

Fig. 4, is a perspective view of another modification.

30 The drawer stabilizer embodying my invention may be used in connection with the ordinary drawer guide A, and comprises a channel strip B and a guide rail D. Ordinarily the channel strip B is secured to the 35 side wall E of a cabinet and the guide rail D is secured to the side walls of a drawer G. However, this may be reversed and the guide rail D may be secured to the wall of the cabinet and the channel strip B be secured 40 to the drawer, as shown in Fig. 3.

The channel strip and the guide rail are formed preferably of sheet metal.

Channel strip B has horizontal walls b, b' which terminate at their outer ends in vertical flanges b², b³, which are screwed to the side walls E of the cabinet. At their inner ends walls b, b' have inwardly projecting beads b⁴, b⁵, which increase in size from the front to the rear of the cabinet, so that between the inner edges of the beads there is formed an inwardly converging way. The inner ends of the beads b⁴, b⁵, terminate in inclined walls b⁶, b⁷. Walls b⁶, b⁷, are of

gradually diminishing width from the front to the rear of the cabinet.

Guide rail D has under cut portions d, d' which form the seats for the beads b⁴, b⁵. These under cut portions are V shaped in cross section, the walls of the V gradually increasing in width from the front to the rear of the guide rail, as shown in Fig. 2. The V shaped or under cut portions of the rail, terminate in inwardly projecting inclined sides d², d³, which decrease in width from the front to the rear of the rail so that the walls b², b³ with the inner walls of the V shaped portions d, d', form an under cut head upon the rail, which tapers from the front to the rear. The rail has at its inner ends vertical flanges d⁴, d⁵, which are screwed to the walls G of the drawer. In the modification shown in Fig. 4, the webs d⁴, d⁵, are formed in alinement with the inner walls of the V shaped portions d, d'.

In use the tapered head of the rail engages the tapered groove formed by the inwardly projecting beads of the channel, which likewise tapers from the front to the rear, and therefore gradually guide the drawer to an accurate position as it is closed. When the drawer is closed the beads upon the channel strip become firmly locked in the under cut portions of the guide rail and therefore oppose any lateral movement between the drawer and the sides of the cabinet. Because of the under cut portions of the rail and the beads on the channel strip being tapered gradually from the front to the rear, the tapered portion and the beads will contact only when the drawer is in a closed position.

While I have described my invention, as applied to a drawer and its casing, it may be applied to other sliding members and their casings.

What I claim is:—

1. In a drawer stabilizer the combination with a cabinet wall and a drawer, of a channel strip mounted upon the cabinet wall and having formed in it a longitudinal dove-tailed groove, and a guide rail mounted on the drawer and having formed upon it a head with under-cut sides and adapted to fit the dove-tailed groove of the channel strip in the closed position only of the drawer.

2. In a drawer stabilizer the combination with a cabinet wall and a drawer, of a channel strip mounted upon the cabinet wall and having formed in it longitudinal dove-tailed groove tapering toward the rear, and a rail mounted on the drawer and having formed upon it a head with under-cut sides tapering toward the rear and adapted to fit the
- 5 dove-tailed groove of the channel strip when in a closed position and to secure the drawer 10 against vertical and lateral movement.

In witness whereof, I have hereunto subscribed my name this 24th day of December, 1919.

WILLIAM F. STREICH.
